ADJUSTABLE BLIND OR AWNING

Kenneth W. Pettigrew, Cranston, and Charles A. Kilvert, Jr., Providence, R. I., assignors to Rhode Island Engineering and Manufacturing Corporation, Central Falls, R. I., a corporation of Rhode Island

Application March 21, 1949, Serial No. 82,531

4 Claims. (Cl. 20—57.5)

1

This invention relates to improvements in Venetian-type metallic blinds or awnings.

A principal object of the invention is the provision of a structure of louvers having novel construction and control features which make it adaptable to a variety of window conditions. Another object is to provide a louver structure with controls which with a minimum of structural alterations is adaptable for use either as a blind or as an awning.

A special object of the invention is the provision of a novel form of louver control in the form of a gear assembly carried on the louver structure, the features whereof permit adjustment of the angle of the louvers either from inside or outside the window. This gear control thus may be used to regulate the louvers from alternate locations, usually to be determined by whether the structure is employed as a blind or as an awning. The said control, when connected for interior control of the louvers, eliminates gears, gear boxes, or other controls inside the window which in some room conditions are difficult to mount conveniently. The unsightliness of such controls is likewise eliminated, and an adaptability to a wider range of window conditions is provided. For example, the interior control of the present invention may enter the building through the mullion between window panes if necessary, since no bulky interior control mechanism is required, and the interior control crank of the invention does not require a strong mounting.

In one form of the invention, a blind is provided which shields the window at a fixed angle (approximately 10 degrees from the vertical), the louvers of which are adjustable from inside the window and may be completely closed to provide a storm proof closure. The louvers may also be opened to an angle beyond the horizontal, so that sunlight may be reflected into the room if desired.

In a second embodiment of the invention, a structure is provided which is primarily intended for use as an awning (at an angle of about 45-60 degrees with the building, for example) which, however, may be adjusted to any angle desired for an awning and also be partly or completely closed over the window to take the position of a blind. When completely closed over the window, special arrangements are provided so that the structure may be firmly fastened or locked shut against the window. In this position the blind constitutes ideal storm protection, and will resist damage from high winds or hurricanes.

2

In a third form of the invention, the adaptability of the louver control mechanism is illustrated in an embodiment having the control mounted near the top of the louver structure.

5 This embodiment is likewise usable as an awning or blind.

Further objects of the invention are to provide awnings or blinds which are of extremely sturdy construction, formed of parts easily obtainable from commercial sources and easily

10 adapted according to the invention. The structures herein described require minimum maintenance, and afford superior control over light and heat.

15 Preferably, awnings or blinds according to the invention are made of aluminum, although other materials may of course be employed. Aluminum is preferred because of its light weight, its ability to reflect light and heat, its attractive appearance and because it requires no paint or other coating.

Other and further objects and advantages of the invention will be described in connection with the figures of the drawings, wherein:

20 25 Fig. 1 is a front elevation of one embodiment of a blind according to the invention in position on a window frame;

Fig. 2 is a sectional view, with some parts in elevation, on the lines 2—2 of Fig. 1;

30 35 Fig. 3 is an enlarged sectional detail of the upper structure of the blind shown in Fig. 2, illustrating in dotted lines the closed position of the louvers;

Fig. 4 is an enlarged detail, with parts broken away and other parts in section, showing the gear control for the louver adjustment according to the invention;

40 45 Fig. 5 is an enlarged detail of the front brace which holds the fixed angle type blind of the above figures at the proper angle from the building;

Fig. 6 is another enlarged detail showing one of the connecting means between the frame of the blind, and front and cross braces;

45 50 Fig. 7 is a sectional view similar to that of Fig. 2, taken on the lines 7—7 of Fig. 8, illustrating a second modification of the invention, a blind or awning whose angular relationship with the building may be adjusted;

Fig. 8 is a sectional view taken on the lines 8—8 of Fig. 7;

55 55 Fig. 9 is a fragmentary front elevation showing the second modification in closed and locked position;

Fig. 10 is an enlarged detail of the bracket

sliding clamp assembly carried by the side brackets in the second embodiment;

Fig. 11 is an enlarged detail of an angle sliding clamp forming part of the second modification;

Fig. 12 is an enlarged view similar to Fig. 3, showing the upper hood construction of the second embodiment; and

Fig. 13 is a detail of a third embodiment of the invention, in which the louver control mechanism is located near the top of the awning or blind.

In Figs. 1-6 are shown the first embodiment of the invention, a blind which is fixed, in the sense that the angular relationship it makes with the building wall is pre-selected but non-adjustable, whereas the louvers are adjustable throughout a wide arc of swing or tilt. Most of the structural parts of this first embodiment are common to the other embodiments described below. In these figures the casement or window frame is designated at 20, having a mullioned window 21. At the top of the frame and extending inwardly from the outer face of the building to provide a rainproof joint, is the hood 22 which is firmly attached to the building by bolts 23 at spaced intervals. Bolts 23 also carry angle pieces 24 whose lower ends are drilled and to which are fastened recessed angle support members 25, by means of bolts 26.

From members 25 depend the main angle frame members 27, 28, and 29, attached to members 25 by bolts 30. It will be seen that each of the main angle frame members is mounted to present a flat side inwardly toward the window, leaving the other side with the edge facing outwards. As shown in Figs. 1 and 2, the main angle frame members extend downwardly and at a small angle with the building, and terminate at a point so that the blind will cover approximately four-fifths of the window. Obviously the construction can be extended to cover the entire window if desired.

Near their lower ends, the frame members 27, 28 and 29 are fastened together and to the building by the tubular front support 31, which is of ordinary pipe construction, and hence cheap and easy to assemble in various widths. Midway of the frame members is located a tubular cross brace 32, of the same material as support 31. A detail of support 31 is shown in Fig. 5 wherein it is obvious that the two end caps 33 of support 31 are designed to be attached to the building wall at each side of the window by suitable bolts or screws, as shown in Fig. 1.

Support 31 and brace 32 are connected to frame members 27, 28, and 29 by a number of clamping members, a detail of one of which is shown in Fig. 6, and which comprises a U-bolt 34, spacer 35, washers 36 and nuts 37. Spacer 35 is so designed that its faces fit the round pipe 38 at one end and the flat side of the frame members at the other. Pipe 38 may, as aforesaid, either be part of the support 31 or the brace 32.

The structure thus far described provides ample framework and supporting means for a large sized blind, but it will be obvious, however, that the size of the particular window will determine the number required of members such as the frame members 27, 28, and 29, and brace 32.

The louver construction and adjusting mechanism will next be described for the embodiment of Figs. 1-6.

The louvers 40 are preferably formed of flat

strips of aluminum and are of equal size except for louver 40a at the top which is slightly wider, as best shown in Fig. 3, in order to reach under the depending tip 42 of the hood 22 in all positions of adjustment. The outer edges 43 of all louvers are bent downwardly and their inner edges 44 bent upwardly at angles of 90 degrees, so that in closed position they interlock, as shown in dotted lines in Fig. 3.

Likewise, it will be seen that the inner edge of louver 40a interlocks with the tip 42 of hood 22. By this means extremely good storm resistant joints are provided throughout the blind.

The louvers are supported in cantilever fashion and are connected to each of the main frame members 27, 28 and 29 by a plurality of pivoted hinge members 45. These hinge members may be cut from flat stock and provided with a bent-over seat portion 46 for attachment to the underside of the louvers, as by riveting or bolting. As best seen in Fig. 3, the vertical portion of hinge members 45 is roughly triangular with the longest arm beneath the louvers. Members 45 are drilled with holes providing pivot points and attached to the frame members (27 in Fig. 3) by rivet connections 47. By this arrangement the louvers 40 always tend to close, their weight being unbalanced in this direction, and this tendency is desirable for the purpose of eliminating "flutter" which would otherwise be caused by the wind if the louvers were equally balanced on the hinge members 45. Also, by this arrangement, tension is provided at the pivot points, and throughout the control and linkage mechanism yet to be described, which eliminates rattling.

The inward tips of hinge members 45 are drilled to receive rivet connections, and as seen in Figs. 2-3, the set of hinge members mounted on frame piece 27 are connected together at spaced intervals by a linkage bar 48 and rivets 49. The lower tip of linkage bar 48 is connected to the gear control mechanism at rivet 50.

As best seen in Figs. 2 and 4, the lowest louver 40b at its point of connection with frame member 27 does not carry a hinge member of the type of hinge 45, but instead is connected by bolts 51 to a member 52 comprising a combination internal gear swivel and hinge. Gear swivel 52 is pivoted at rivet 53 to the frame member 27 and connected to the linkage bar 48 at rivet 50. Swivel 52 is provided with a semi-circular or planetary sector of internal gear teeth 54. A housing 56, partly shown in Fig. 4, may be provided for the swivel 52, on the inside of which is cut a semi-circular slot 55.

On the opposite side of frame member 27 from the swivel 52 is mounted a gear box 57 containing a worm wheel 58 mounted on a shaft 59. Shaft 59 passes through the wall of gear box 57, frame 27 and into housing 56 through slot 55, where it carries a reduction gear 60 meshing with the teeth 54 of swivel 52.

Worm wheel 58 is driven by worm gear 61 mounted on a shaft 62 which passes through frame 27 in the direction of the window casement 20. Shaft 62 is illustrated as entering the window through a mullion 65 (Fig. 2) and terminating in a crank 66. It is usually preferable to render the shaft 62 flexible by interposition of universal joints such as indicated at 63 and 64 in Fig. 2. By such joints a wide selection may be made for the entry point of the shaft through the window.

From the foregoing description it will be seen

that operation of the crank 66 imparts tilting movement to the louver 40b through the gears 61, 58, 60 and 54, and as movement is imparted to the swivel 52, linkage bar 48 is raised or lowered and the other louvers 40 and 40a connected to it are raised or lowered in unison with louver 40b.

The louver control mechanism above has been described as being mounted on frame member 27 at the left side of the window appearing in Fig. 1. The mechanism may obviously be mounted on any one of the frame members 27, 28, or 29 by the expedient of mounting the gears and connecting the link bar with the appropriate set of hinges 45. Likewise, by appropriate spacing of the frame member carrying the control and/or by utilizing the flexibility of the shaft 62 provided in the universal joints 63 and 64, the shaft 62 may be introduced through the side or bottom frame of the window or the wall of the building as circumstances dictate.

The second embodiment will next be described with reference to Figs. 7-12. This embodiment may be termed an adjustable awning, although its range of adjustment is such that it may be completely closed against the window to take a position normally occupied by a blind or shutter. This embodiment has many common parts to that of the first embodiment which have been given the same numerals and will not be described again.

In Figs. 7-12, the awning illustrated is attached to the outside of the building wall 67 directly above the window 21a. For this purpose a support casting 68, whose shape is best seen in Fig. 12, is screwed or bolted to the wall by fasteners as indicated at 69. The upper side of casting 68 presents a flat surface on which the hood 70 is suitably bolted by bolts 71. The lower edge of the casting 68 is provided with a plurality of spaced pivot connections such as connection 72 shown in the figures, it being understood that there are as many of such connections as are required by the width of the blind and the number of main angle frame members required. There are three such angle frame members shown, 27a, 28a and 29a, Fig. 8. These angle frame members are attached to angle supports 25 which in turn are attached to pivot connections 72 by bolts 73, it being understood that these bolts form the axis of swing for the awning in its various angles of adjustment.

In the second embodiment, the construction of louvers 40, 40a and 40b remains as previously described, also the disposition of the pivoted hinge members 45 (not visible in Fig. 7) and linkage bar 48. Also a cross brace 32a may be provided, of the same type of brace 32 only located near the end of the awning, and attached in similar manner as described for Fig. 6.

Likewise, the louver adjusting mechanism is the same as described for Fig. 4, with the exception that the crank shaft (compare 62 in Fig. 4) terminates just beneath the frame member 27a in a socket 74 which is rotatable by a detachable crank 75 of suitable length.

The awning angle adjusting mechanism includes two vertical side braces or guide bars 76 affixed to the wall 67 at either side of window 21a. These guide bars are preferably of the simple and cheap construction described for the tubular front support 31.

Guides 76 each carry a split-sleeve sliding clamp 77 carrying star nuts 78 for tightening the clamps 77 on guides 76 at the desired position of

awning angle. The supporting arms 80 and 81 are mounted for horizontal and vertical pivoting on guides 76 through hinge lugs 82, as best seen in Fig. 10. At their extended ends, arms 80 and 81 are slightly bent and connected to the angle frame members 27a and 29a through the means of the angle sliding clamps 83 and 84, a detail of one of which is shown in Fig. 11, connected to the arm 80 by a bolt 85 and carrying a set-screw 86 whereby the angle clamps may be fixed at any selected point on the angle frame members.

It follows from this construction that the awning of Figs. 7-12 may be adjusted at any desired angle customary for awnings. Additionally, the construction is such that, as shown in Fig. 9, by detaching arms 80 and 81 from the angle sliding clamps 83 and 84 by removal of bolts 85, the awning may be lowered to vertical position against the window in the position of a storm shutter, and the two arms 83 and 84 locked to each other, as by a padlock 87 passed through two holes 88 in arms 83 and 84. Obviously, if padlock 87 is not needed for added security, a mere bolt or pin through holes 88 will serve as well for the purposes of a hurricane shutter.

To permit the wide angle of swing designed in this embodiment an upper semi-circular louver 40c is mounted on the angle supports 25 by bolts 89 in the position shown in Fig. 12. This louver is fixed to supports 25 and pivots along with frame members 27a, 28a and 29a on the axis of bolts 73. Louver 40c is provided with a downwardly bent lower edge 90 which overlaps edge 44 of louver 40a when the latter is in closed position. The upper edge 91 of louver 40c is upwardly bent and regardless of the angle of adjustment will remain beneath the hood and inside of the downwardly bent lower edge 92 of hood 70. Thus a weatherproof but adjustable joint is provided.

In Fig. 13, a third modification of the invention is shown, which illustrates the extreme adaptability of the louver adjusting mechanism. In this view, the louver control mechanism with parts as previously identified, is shown mounted to directly operate a louver 40d, connected with other louvers such as upper louver 40a by means of linkage bar 48a. The shaft 62a may be rotated through socket 74a and detachable crank 75a. The control mechanism is thus mounted toward the top of the louver structure in this view, instead of at the bottom of the blind or awning as in the previous views. A construction such as illustrated would be applicable to the first embodiment if under certain conditions it were desired for the controls to be made from or through the top of the window or casement, or in the case of the awning of the second embodiment, if it were desired to operate the louvers from within the window, as would be necessary in the case of awnings above the ground floor.

Obviously, according to the invention, the louver controls may be directly connected to any louver of the series as circumstances require.

In the claims below, the word "casement" is used in the ordinary sense to designate the apertures usually formed in buildings to accommodate windows used for ventilation and for show windows or the like, but the word should also be construed to include all building apertures, such as doorways, for example, to which the blind or awning of the inventor could be applied.

Having thus described the invention, what is claimed is:

1. An adjustable louvre structure of the char-

acter described, for attachment to a building for the protection of a casement therein, comprising: a supporting frame consisting of a plurality of spaced elongated depending frame members pivotally hinged to the building above the casement, the side frame members whereof being supported at a selected angle from the building by means of a pair of vertically disposed braces attached to the building at opposite sides of the casement, and supporting arms at their inner ends slidably adjustably mounted on said side braces, and at their outer ends pivotally and detachably connected to said side frame members, said arms carrying innerconnecting means adjacent their outer ends for linking said arms together over said louvre structure when said structure has been swung flat against said casement; a plurality of lateral spaced overlapping louvres pivotally mounted transversely of said depending frame members; a linkage control bar connecting said louvres; and louvre control mechanism carried by one of said frame members and connected to a selected one of said louvres for adjusting the pitch of all of said louvres.

2. An adjustable louvre structure of the character described, for attachment to a building for the protection of a casement therein, comprising a supporting frame consisting of a plurality of spaced elongated depending frame members pivotally connected with the building over the casement, the side frame members whereof being supported at a desired angle with the building by a pair of arms carried on the building at either side of the casement, said arms being adjustably and detachably connected to said side frame members; a plurality of spaced laterally disposed overlapping louvres pivotally mounted on said frame by pivoted hinge members having pivot connections on said frame and supporting said louvres on arms formed on said hinge members extending outwardly from said frame; said hinge members having other arms extending inwardly from said pivot connections and linked together by a linkage control bar; and louvre control mechanism including a hinged swivel supporting one of said louvres on the frame in the same pivotal relationship common to the other louvers and carrying a gear, and other gear means supported on the frame adjacent said hinged swivel and connected to said gear for adjusting the angle of the louvers; and locking means provided in the pair of arms supporting the side frame members, whereby the structure may be swung against the casement and the said arms detached from said frame members and locked together over the structure.

3. An adjustable louvre structure of the character described, for attachment to a building for the protection of a casement therein, comprising a supporting frame consisting of a plurality of spaced depending frame members pivotally connected with the building above the casement, the side frame members being supported at the desired angle with the building by a pair of arms, said arms being attached to said side frame members by clamping means shaped to fit over and selectively grip a portion of each of said frame members, said arms also being vertically adjustable at their point of connection with the building, said connection being by means of a pair of vertically disposed guides each disposed on the building adjacent opposite sides of the casement,

said guides carrying adjustable clamps connected to said arms and operable from within said casement; a plurality of spaced laterally disposed overlapping louvres pivotally mounted on said frame by pivoted hinge members having common pivot connections on said frame and supporting said louvres on arms formed on said hinge members extending outwardly from said frame; said hinge members having other arms extending inwardly from said pivot connections and linked together by a linkage control bar; and louvre control mechanism including a hinged swivel supporting one of said louvres on the frame in the same pivotal relationship common to the other louvers and carrying a gear, and other gear means supported on the frame adjacent said hinged swivel and connected to said gear for adjusting the angle of the louvers.

4. An adjustable louvre structure of the character described, for attachment to a building wall over the exterior of a casement therein, comprising a supporting frame consisting of a plurality of spaced parallel angle frame members depending from the building above said casement, one angle segment of said angle frame members being disposed at substantially 90 degrees with respect to said casement, and lower supporting means connecting said angle frame members together and supporting same at a predetermined angle with the vertical with respect to said building wall and casement; a plurality of louvres pivotally supported transversely of said angle frame members by hinge means uniformly pivotally mounted on the said 90 degree angle segment of said angle frame members; a linkage control bar pivotally connecting said hinge means; and louvre control means comprising a pivoted swivel carrying an internal gear sector, said swivel being mounted on the side of one of said 90 degree angle segments remote from the angle formed by said angle member, a reduction gear shafted through said 90 degree angle segment and engaging said internal gear sector, a gear box carried in the angle formed by said angle member and enclosing a worm wheel connected to said reduction gear, and a worm gear driving said worm wheel, said worm gear being connected through the angle member by a drive shaft extending interiorly of said lower structure.
